UNITED STATES PATENT OFFICE.

FREDERICK H. RITTENOUR, OF ANNAPOLIS, MARYLAND.

SPEEDOMETER FOR AUTOMOBILES.

1,375,761.

Specification of Letters Patent. Patented Apr. 26, 1921.

Application filed June 6, 1918. Serial No. 238,504.

To all whom it may concern:

Be it known that I, FREDERICK H. RITTENOUR, a citizen of the United States, residing at Annapolis, in the county of Anne 5 Arundel and State of Maryland, have invented certain new and useful Improvements in Speedometers for Automobiles, of which the following is a specification.

This invention is in the nature of a recording speedometer for automobiles and the 10 objects of the invention are to generally improve such instruments whereby the operator will have a record of the number of miles run each day, the speed at which the machine 15 was run, the day of the month, and the time of day.

With these objects in view the invention consists in the improved construction, arrangement and combination of parts herein- 20 after fully described and afterward particularly claimed.

In order that the construction and operation thereof may be readily comprehended, I have illustrated in the accompanying 25 drawings an approved embodiment of my invention and will now proceed to fully describe the same in connection with said drawings in which—

Figure 1 represents a front elevation of 30 the invention constructed to be driven by mechanical means, with parts in section and parts in dotted lines;

Fig. 1^a, a side view of the pencil linkage and connections;

Fig. 2, a partial plan view of the construction shown in Fig. 1,

Fig. 3, a side elevation partly in section,

Fig. 3^a, a detail view of parts of the mechanism shown in Fig. 3,

Fig. 4, a partial view, in elevation of the dash board of an automobile equipped with my speedometer, showing the face of the instrument as exposed to the driver,

Fig. 5, a face view of a dial which I may 45 use to take the place of the hands of a clock, and on which a record is to be made by the speedometer,

Fig. 6 including Figs. 6^a, 6^b, and 6^c, mechanism whereby the pencil may be moved by 50 magnetic induction instead of the mechanical means shown in the other figures, and

Fig. 7, a solenoid for moving the pencil in a modified arrangement.

Like reference characters mark the same

parts wherever they appear in a plurality 55 of the figures of the drawings.

Referring specifically to the drawings 1 indicates a clock mechanism which carries a spool 2 fastened to the turning mechanism by a pin 3 or other suitable means and 60 on such spool is wound, from another spool 4, a tape 5 on which are vertical lines spaced to indicate intervals of time and horizontal lines spaced to indicate variations in speed. In addition to such lines, the actual time, 65 miles per hour, date, etc. are indicated on said tape.

The tape is seated in a grooved guide 6 and a spring 7 is so placed as to bear against the tape on spool 4 and retard its 70 passage therefrom.

In Fig. 1, 8 indicates a small centrifugal pump, the impeller 9 of which when driven by gearing and shaft connected to a moving axle or other part of the automobile, in the 75 direction indicated by the arrow, will draw a liquid (preferably oil) from a well or tank 10 and deliver it into a flattened curved tube 11 causing a static pressure therein proportional to the speed of revolution of 80 the impeller.

Movably attached to the end of the tube 11 is a lever 11^a longitudinally slotted at 11^b through which slot passes a screw 11^c on which the lever is pivoted, the outer end 85 of the lever being pivotally attached at 12^a to a cam 12 pivoted at 12^b.

At 14 is a bar which is pivoted at one end, at 14^a, under which bar the cam 12 bears, the opposite end of the bar being 90 pivotally attached, at 14^b to a link 14^c, which, at its opposite end, is pivotally attached to a block 15^a, which is attached to a rod 13^c which carries a pencil 13 and moves in a vertical guideway 15, as clearly shown 95 in Figs. 1 and 1^a.

Owing to the form of the tube 11, the pressure of the liquid therein will change its form, causing it to tilt the lever 11^a and thus move the cam 12 on its pivot 12^b 100 against the bar 14, thus tilting said bar on its pivot 14^a, causing it to move the link 14^c and this, carrying the pencil 13 with it, will cause the pencil to move over a straight line *a*—*b* on the tape 6.

The bar 14 is held down against the cam by a spring 14^d and the movement of the pencil on the line *a*—*b* will vary with the 105

speed of the automobile, while the tape is moved by the clock, so that the pencil will trace a line on the tape which will be a record of the speed and time.

5 The cam mechanism is necessary only to give equal divisions to the speed lines on the tape, because the static "head" produced by the pump is not directly proportional to the speed. Experiment shows that no matter what the size of the pump, 500 revolutions will raise water 1 foot, 1000 revolutions will raise it 4 feet, 2000 revolutions will raise it 16 feet, and so on. It is therefore necessary to so design the cam in proportion to this resulting head.

10 The well or tank 10 is made deep to insure the pump having a suction "head" and preferably, inside this well or tank are located gears for driving the impeller 9, 20 as shown in Figs. 1 and 3, the gear 16 being loose on the shaft of the impeller, the gear 17 on a stub shaft 17^a and meshing with gears 16 and 18 and the latter with a gear 18^a on a shaft 18^b coupled to a flexible shaft 25 20 which is connected to a wheel or revolving axle of the automobile by worm gearing 19.

21 The gear 16 is loose on the impeller shaft 21 and drives that shaft through a ratchet 30 wheel 22 secured thereon, a pawl 23 pivoted on gear 16 engaging the teeth of the ratchet wheel and held yieldingly in contact therewith by a spring 24, as shown in Fig. 3^a, whereby, the impeller will be driven in a 35 forward direction only, as indicated by the arrow 9^a in Fig. 1, which prevents the pump running backward when the automobile is backing.

40 Geared to the shaft 18^b, by suitable gearing such as bevel gears *d* and *e*, vertical shaft *f*, and bevel gearing *g*, is an ordinary revolution counter 25, (the interior mechanism of which is not shown), the indicators of which are shown in Fig. 4, which is a 45 partial view of the inner face of the dashboard.

46 The type of instrument thus described is intended to record a week's or a month's or more running. If the instrument is so designed that a record for only one day is 50 desired, a more preferable arrangement is shown in Fig. 5 which is a paper dial, on which are printed radial lines representing time, and circles representing speed. This 55 dial can be made to take the place of the hands of a clock and be revolved, the pencil tracing on it a record as before.

56 Figs. 6^a, 6^b and 6^c show a method of moving the pencil 13 by means of magnetic induction. Fig. 6^a shows the arrangement of the permanent magnets 26. These magnets are fastened to the gear wheel 27 (Fig. 6^b) and are revolved by the flexible shaft 20 as before. They revolve within a metal 65 cup 28 which is pivoted in the bearings.

When the magnets are revolved, the lines of force tend to drag this cup after them. Fastened to the cup is a spring 30, Fig. 6^c, the other end of which is fastened to the bearing or frame 29. The action of this 70 spring is to retard the cup from following the magnets. The amount of this retardation will vary directly as the number of revolutions of the magnets. Fastened also to the cup is the linkage 14^c of Fig. 1, 75 which in turn will move the pencil 13 in the guide 15, as the cup is twisted about its centers.

Fig. 7 represents a solenoid consisting of a coil of wire 31, in which is suspended an 80 iron core 32 fastened to the pencil rod 13^a, which can be made to move the pencil, provided the solenoid is receiving a current of electricity from a small generator substituted for either of the driving mechanisms 85 shown before.

90 The whole instrument will be incased in a box placed preferably behind the dash board of the automobile and accessible only through lock and key.

95 The instrument described is a recording speedometer for an automobile and the benefits to be derived from its use are many, among which the following are mentioned.

1. The owner will have a record of the 95 number of miles he ran each day, the speed at which he ran, the day of the month and the time.

2. This information will be extremely useful to automobile owners, and especially to 100 garage and taxicab companies, inasmuch as it will keep an accurate tally on the chauffeur's record of the time and speed at which the car was running in case of accident, and in case of a question as to whether the car 105 was breaking the speed laws the record shows exactly the speed of the car.

3. The record shows whether the car has 110 been used or not during the absence of the owner.

4. As you can read time from the record no extra clock is necessary.

Other means for driving this speedometer may be used and changes and variations in the construction of the parts illustrated, 115 may be made, within the scope of the appended claims, without departing from the spirit and scope of the invention.

Having thus fully described my invention, what I claim as new and desire to secure by 120 Letters Patent of the United States is;

1. A speedometer for automobiles comprising a moving tape, a pencil and means for moving the pencil over the tape, in a direction transverse to the movement of the 125 tape, said means comprising a curved flattened flexible tube and a pump for forcing a liquid into said tube.

2. A speedometer for automobiles comprising a moving tape, a pencil and means 130

for moving the pencil over the tape, in a direction transverse to the movement of the tape, said means comprising a curved flattened flexible tube, a pump for forcing a liquid into said tube and connections from the tube to the pencil.

3. A speedometer for automobiles comprising a moving tape, a pencil and means for moving the pencil over the tape, in a direction transverse to the movement of the tape, said means comprising a curved flattened flexible tube, a pump for forcing a liquid into said tube and connections from the tube to the pencil, comprising a cam operated by the change of form of the tube caused by the pressure of liquid therein.

4. A speedometer for automobiles comprising a moving tape, a pencil and means for moving the pencil over the tape, in a direction transverse to the movement of the tape, said means comprising a curved flattened flexible tube, a pump for forcing a liquid into said tube and connections from the tube to the pencil, comprising a cam oper-

ated by the change of form of the tube 25 caused by the pressure of liquid therein, links connected with the pencil, a pivoted lever connected with the links and a spring holding the cam in contact with said pivoted lever.

5. A speedometer for automobiles comprising a moving tape, a pencil and means for moving the pencil over the tape, in a direction transverse to the movement of the tape, said means comprising a curved flattened flexible tube, a pump for forcing a liquid into said tube and connections from the tube to the pencil, comprising a cam operated by the change of form of the tube caused by the pressure of liquid therein, a 40 guide for the pencil located transversely to the tape, links connected with the pencil, a pivoted lever connected with the links and a spring holding the cam in contact with said pivoted lever.

In testimony whereof I affix my signature.

FREDERICK H. RITTENOUR.
